DESIGN FOR AN ACCORDION

Antonio Butti, New York, N. Y.

Application January 14, 1938, Serial No. 74,287

Term of patent 14 years

To all whom it may concern:

Be it known that I, Antonio Butti, a citizen of the United States, residing at the city of New York, in the county of New York and State of New York, have invented a new, original, and ornamental Design for an Accordion, of which the following is a specification, reference being had to the accompanying drawing, forming part thereof.

In the drawing:

Fig. 1 is a front view of an accordion showing my new design;

Fig. 2 is a top plan view thereof;

Fig. 3 is an end view of the same; and

Fig. 4 is a fragmental side view of one of the keys of the keyboard, all of the keys having the same curvature.

The essential feature of my new design is the longitudinally curved upper surface of the keys composing the keyboard of the accordion, as more particularly shown in Figs. 3 and 4.

I claim:—

The ornamental design for an accordion, as shown and described.

ANTONIO BUTTI.
